UNITED STATES PATENT OFFICE.

JACOB SCOLL, OF EVANSTON, ILLINOIS.

DESIGN FOR A DOLL.

Application filed August 22, 1923. Serial No. 7,061. Term of patent 3½ years.

To all whom it may concern:

Be it known that I, JACOB SCOLL, a citizen of the United States, residing at Evanston, county of Cook, and State of Illinois, have invented a new, original, and ornamental Design for Dolls, of which the following is a specification, reference being had to the accompanying drawing, forming a part thereof, and in which the figure is a perspective view of a doll showing my new design.

I claim:

The ornamental design for a doll, as shown.

Signed at Mellen, in the county of Ashland and State of Wisconsin, this 13th day of August, 1923.

JACOB SCOLL.
